(57) **CLAIM**

The ornamental design for an inverter generator, as shown and described.

DESCRIPTION

FIG. 1 is a front perspective view of one embodiment of an inverter generator of the present invention.

FIG. 2 is a right-side view of the inverter generator of FIG. 1.

FIG. 3 is a left-side view of the inverter generator of FIG. 1.

FIG. 4 is a front view of the inverter generator of FIG. 1.

FIG. 5 is a rear view of the inverter generator of FIG. 1.

FIG. 6 is a top view of the inverter generator of FIG. 1; and,

FIG. 7 is a bottom view of the inverter generator of FIG. 1.

The broken line showing of the environment is for illustrative purposes only and forms no part of the claimed design. The broken lines which define the boundaries of the claimed design form no part thereof.

1 Claim, 7 Drawing Sheets
